FLUID CYLINDER AND PISTON ASSEMBLY

Jack J. Sendoykas, St. Clair Shores, Mich.

Application April 23, 1958, Serial No. 730,332

9 Claims. (Cl. 121—38)

This invention relates to new and useful improvements in fluid motors.

More particularly, the fluid motor of this invention comprises a cylinder having a piston mounted for reciprocation therein and novel means for controlling the rate of travel of the piston as it advances in the cylinder. The motor is intended to be used wherever it is desired that a part actuated by the piston move at different speeds during different portions of the piston stroke. For example, it is contemplated that the motor be used on a clamping fixture where it is necessary or desirable for the clamp to advance initially on a rapid traverse and then continue to advance slowly to a final clamped position. In another typical situation the motor is connected to the grinding head of a grinding machine so as to first advance the head on a rapid traverse to bring the head up to the work and then move it slowly during the actual grinding operation. A similar situation is presented by a machine tool having tools for performing a cutting operation on a work-piece. In still other situations it is desirable to have the motor advance a tool or other part in a series of steps which are alternately rapid and slow.

The above are typical environments in which the motor of this invention is adapted to perform. Other typical situations will be readily apparent to those skilled in the art.

An important object of the present invention is to provide a fluid motor of the above mentioned character that is uniquely constructed and readily adaptable to the particular mode of operation required of it.

Another object of the invention is to provide a fluid motor of the above mentioned character that is uniquely constructed so that it can be changed by inexpensive means from one mode of operation to a different mode of operation.

Still another object of the invention is to provide a fluid motor of the above mentioned character that is inexpensive to manufacture and efficient in operation.

Other objects and advantages of the invention will be apparent during the course of the following description.

In the drawing forming a part of this specification and wherein like numerals are employed to designate like parts throughout the same.

Figure 1 is a longitudinal sectional view of a fluid motor embodying the invention, showing the piston fully retracted in the cylinder and the speed control mechanism positioned to permit an essentially rapid initial traverse of the piston.

Fig. 2 is a view similar to Figure 1 but showing the piston advanced in the cylinder and the speed control mechanism positioned to slow the rate of advancement of the piston.

Fig. 3 is a view similar to Figures 1 and 2 but showing the piston fully advanced in the cylinder, and

Fig. 4 is a longitudinal sectional view of a modified motor embodying the invention, and particularly showing a modified speed control mechanism for advancing the piston in a series of alternate rapid and slow movements.

Considered in certain of its broader aspects the fluid motor of this invention comprises a cylinder having a fluid inlet at one end and a fluid outlet at the other end thereof. A tube extends from the inlet axially into the cylinder for conducting fluid from the inlet and this tube has an enlarged terminal portion which is provided with at least one lateral fluid discharge opening. A piston is mounted for reciprocation in said cylinder and along said tube, and the end of the cylinder behind the piston has a by-pass which extends between the inlet and the interior of the cylinder behind the piston. The by-pass is continuously open so that fluid can flow therethrough from the inlet into the cylinder; but the flow is controlled by a needle valve or the like to a relatively restricted rate. A piston rod carried by the piston extends therefrom through the forward end of the cylinder; and the piston rod has a tubular portion which telescopically receives the tube. Fluid also flows from the inlet through the tube to the forward end thereof where it discharges through the lateral opening and into the piston rod which conducts it back into the cylinder behind the piston. The piston rod is formed with a portion or portions of relatively small diameter and with a portion or portions of relatively large diameter. The portion or portions of relatively small diameter snugly fit the terminal portion of the tube to close the opening and to restrict flow of fluid into the cylinder to the by-pass. The portion or portions of relatively large diameter are spaced circumferentially from the terminal portion of the tube to provide relatively unrestricted communication between the opening and the cylinder behind the piston. Thus, when a relatively large diameter of the rod is in register with the end of the tube, fluid flows rapidly into the cylinder and advances the piston at an essentially rapid rate; however, when a relatively small diameter portion of the rod is in register with the opening the restricted flow of fluid through the by-pass fills the cylinder slowly and advances the piston at an essentially slow rate.

It is a feature of the invention that the tube can be removed comparatively easily and quickly from the cylinder for cleaning or replacement. Another feature of the invention is that the piston rod is made in two parts. The inner part of the rod functions as a liner, and the liner is the part of variable internal diameter which controls the advancement rate of the piston. Thus, in order to change the advancement pattern of the piston and to adapt the motor for one job or another it is merely necessary to change the liner of the piston rod. This liner is an easily formed, inexpensive part. Furthermore, the motor is uniquely constructed so that the liner can be easily removed and a replacement liner substituted therefore.

For a more detailed description of the motor, attention is directed to the accompanying drawings wherein the numeral 10 designates a cylinder comprising a tubular wall 12 and front and rear end walls or heads 14 and 16. The forward end of the tubular wall 12 is set in an annular groove 18 in the head 14 and the opposite end of the tubular member 12 is set in an annular groove 20 in the rear head 16. The heads 14 and 16 preferably are generally square in plan. Screws 22 at the corners of the rear head 16 extend forwardly exteriorly of the tubular members 12, through the front forward head 14, and nuts 24 on the screws hold the various parts of the cylinder 10 securely assembled.

A piston 26 is mounted for reciprocation in the cylinder 10 and a piston rod 28 connected and movable with the piston extends forwardly through a central opening 30 in the head 14. A threaded stud 32 on the outer end of the rod 28 adapts the latter for connection to a mechanism to be actuated thereby.

The piston 26 comprises front and rear annular plates

34 and 36 and an intermediate annular disk 38. The rear plate 36 has a forwardly projecting central embossment 40 which receives and snugly fits the intermediate disk 38 and is threaded on the piston rod 28. A collar 42 on the rod ahead of the piston 26 seats forwardly against an annular shoulder 44 on the rod 28 and rearwardly against the front plate 34. Piston rings 46 and 48 have radially inwardly extending portions confined between the disk 38 and the plates 34 and 36 respectively and outer annular portions which fit snugly around the plates 34 and 36 to seal the piston against the wall of the cylinder 10. A radially inwardly extending annular lip 50 on the rear plate 36 overlays the end of the rod 28. Manifestly, when the plate 36 is tightened on the rod 28, all parts of the piston assembly are pulled and held securely together. However, the piston can be readily removed from the cylinder 10 by removing the head 16, and the rod 28 can then be removed from the piston by unscrewing the connection between the rod and the plate 36.

Fluid is admitted into the cylinder 10 behind the piston 26 through a fitting 52 disposed centrally in the rear cylinder head 16. A central passage 54 in the fitting 52 is formed with a threaded socket 56 at the outer end thereof which is adapted to receive a correspondingly threaded nipple on a pipe or tube (not shown) from any suitable source of fluid under pressure.

As clearly shown in the drawings the portion of the piston rod 28 adjacent to the piston 26 is hollow or tubular in form and a tube 58 connected to the fitting 52 extends inwardly from the passage 54 into the hollow portion of the rod 28. A cup-shaped member 60 on the distal end of the tube 58 closes the end of the latter, and fluid traversing the tube 58 is discharged through lateral openings 62 in the tube and member 60.

In the form of the invention here shown the piston rod 28 is formed with an inner liner 64 having a portion 66 adjacent to the piston 26 of relatively small internal diameter and a portion 68 remote from the piston of relatively large internal diameter. As shown in Figure 1, the portion 68 of the liner 64 is substantially larger in diameter than the terminal member 60 so that when the portion 68 is in register with the openings 62 fluid discharging from the tube is conducted back through the rod 28 and into the cylinder behind the piston 26. Also it will be observed that flow of fluid in this manner is relatively unrestricted so that the cylinder 10 is able to fill relatively quickly to push the piston 26 forwardly at a relatively high rate of speed. As the piston 26 advances it of course pushes the piston rod 28 forwardly with it to actuate whatever mechanism is attached to the rod.

The piston continues to advance in the above manner until the relatively small portion 66 of the liner 64 moves into register with the terminal member 60, as shown in Fig. 2. The relatively small diameter portion 66 fits the terminal member 60 essentially snugly as shown in Fig. 2 of the drawing and when it moves into register with the openings 62 it prevents continued flow of the fluid from the tube 58 into the cylinder 10.

In order to provide for continued advancement of the piston 26 after the small diameter portion 66 of the liner 64 closes the openings 62 a by-pass is provided in the cylinder head 16. The by-pass comprises a plurality of radial passages 70 which extend outwardly from the central passage 54 in the fitting 52 and terminate in an annular groove 72 sealed by O-rings 74 and 76. The groove 72 communicates with an L-shaped passage 78 in the head 16, which passage is provided with a tapered seat 80 adapted to receive the correspondingly tapered end of a needle valve 82 which extends radially into the head 16 and is in threaded engagement therewith. The valve 82 extends radially outwardly from the head and a nut 84 on the projecting end thereof is tightened against the head 16 to hold the valve in a selected adjusted

position. In this connection, it will be observed that the valve 82 can be backed away from its seat 80 to permit a limited restricted flow of fluid through the by-pass into the cylinder behind the piston 26. Further, it will be observed that when flow through the openings 62 is stopped by the relatively small diameter portion of the liner 64 in the manner hereinabove described, fluid may continue to flow into the cylinder through the by-pass at a relatively restricted controlled rate so that the piston 26 continues to advance after the openings 62 are closed but at a slower rate of speed. The rate of travel of the piston 26 under these conditions can of course be controlled by adjusting the needle valve 82.

Fluid in the cylinder 10 ahead of the piston 26 is discharged from the cylinder through an annular passage 86 and a lateral port 88 provided in the front cylinder head 14. Conversely, fluid can be admitted into the cylinder through the port 88 and passage 86 ahead of the piston to retract the latter. As the piston 26 is retracted in the cylinder 10, fluid is discharged through a port 90 in the head 16. The passage 54 and the ports 88 and 90 can be connected into a suitable fluid system controlled by a conventional four-way valve in the usual manner to operate the motor in accordance with the requirements of the mechanism to which it is attached.

It will be readily appreciated that the piston rod 28 can be made in one piece if desired but it preferably is made with a removable liner 64, as shown in the drawing. When the rod 28 is made in this manner, the liner 64 can be readily removed if desired and replaced by a liner having a different arrangement of the relatively large diameter portions and the relatively small diameter portions or by a liner in which these portions are of different lengths to adapt the motor to different traverse and speed motions. Replacement liners can be kept on hand and the same motor used to service different machines alternately if desired. As pointed out hereinabove, the rod 28 and the liner 64 can be readily disconnected from the piston for purpose of replacement. In order to hold the liner securely in the rod 28 the annular lip 50 of the piston plate 36 extends inwardly sufficiently far to overlap the end of the liner.

The form of the invention shown in Fig. 4 is identical to the form of the invention first described except for the internal configuration of the liner 64. In this form of the invention a modified liner 92 is provided having a relatively large diameter portion 94, a relatively small diameter portion 96, a relatively large diameter portion 98 and a relatively small diameter portion 100 arranged in series from the distal end of the liner. This configuration of the liner 92 alternates rapid and slow movements of the portion 26. Other variations in the liner will be apparent from the forms shown.

What is claimed is:

1. A variable speed fluid motor comprising a cylinder having a fluid inlet at one end and a fluid outlet at the other end thereof, a tube extending from the inlet axially into said cylinder for conducting fluid from said inlet and having an enlarged terminal portion provided with a lateral discharge opening for said fluid, a piston mounted for reciprocation in said cylinder and along said tube, a by-pass between said inlet and the interior of said cylinder behind said piston providing a continuously open passage through which fluid can flow from said inlet into said cylinder at a relatively restricted controlled rate, and a piston rod movable with said piston extending through said other end of said cylinder and having a tubular portion telescopically receiving said tube and adapted to conduct fluid from said discharge opening into the cylinder behind said piston, at least a portion of said rod snugly fitting the terminal portion of said tube to close said opening and at least another portion of said rod being spaced from said terminal portion to provide relatively unrestricted communication between said opening and said cylinder behind said piston.

2. A variable speed fluid motor comprising a cylinder having a fluid inlet at one end and a fluid outlet at the other end thereof, a tube extending from the inlet axially into said cylinder for conducting fluid from said inlet and having an enlarged terminal portion provided with a lateral discharge opening for said fluid, a piston mounted for reciprocation in said cylinder and along said tube, a by-pass between said inlet and the interior of said cylinder behind said piston providing a continuously open passage through which fluid flows from said inlet into said cylinder at a relatively restricted controlled rate, a piston rod movable with said piston extending through said other end of said cylinder and having a tubular portion telescopically receiving said tube adapted to conduct fluid from said discharge opening into the cylinder behind said piston, a predetermined length of said tubular portion adjacent to said piston snugly fitting the terminal portion of said tube to close said opening to provide a relatively slow advancement for said piston in accordance with flow of fluid through said by-pass and a predetermined length of said tubular portion remote from said piston being spaced circumferentially from said terminal portion to provide relatively unrestricted communication between said opening and said cylinder behind said piston and a relatively rapid initial traverse for the piston.

3. A variable speed fluid motor comprising a cylinder having a fluid inlet at one end and a fluid outlet at the other end thereof, a tube extending from the inlet axially into said cylinder for conducting fluid from said inlet and having an enlarged terminal portion provided with a lateral discharge opening for said fluid, a piston mounted for reciprocation in said cylinder and along said tube, a by-pass between said inlet and the interior of said cylinder behind said piston providing a continuously open passage through which fluid can flow from said inlet into said cylinder at a relatively restricted controlled rate, and a piston rod connected to and movable with said piston extending through said other end of said cylinder and having a tubular portion telescopically receiving said tube adapted to conduct fluid from said discharge opening into the cylinder behind said piston, at least one portion of said tubular portion snugly fitting the terminal portion of said tube to close said opening to stop the flow of fluid through said tube into said cylinder and to restrict entry of fluid into said cylinder to flow through said by-pass, at least one other portion of said tubular portion being substantially larger in diameter than said terminal portion whereby relatively unrestricted communication is provided between said opening and the cylinder behind the piston when said last mentioned portion is in register with said opening.

4. A variable speed fluid motor comprising a cylinder having a fluid inlet at one end and fluid outlet at the other end thereof a tube extending from the inlet axially into said cylinder for conducting fluid from said inlet and having an enlarged terminal portion provided with a lateral discharge opening for said fluid, a piston mounted for reciprocation in said cylinder and along said tube, a by-pass between said inlet and the interior of said cylinder behind said piston providing a continuously open passage through which fluid flows from said inlet into said cylinder at a relatively restricted controlled rate, a valve controlling said by-pass adjustable to regulate the rate of flow through said by-pass, and a piston rod movable with said piston extending through said other end of said cylinder and having a tubular portion telescopically receiving said tube adapted to conduct fluid from said discharge opening into the cylinder behind said piston, at least a portion of said rod snugly fitting the terminal portion of said tube to close said opening and at least another portion of said rod being spaced from said terminal portion to provide relatively unrestricted communication between said opening and said cylinder behind said piston.

5. A variable speed fluid motor comprising a cylinder having a fluid inlet at one end and a fluid outlet at the other end thereof, a tube extending from the inlet axially into said cylinder for conducting fluid from said inlet and having an enlarged terminal portion provided with a lateral discharge opening for said fluid, a piston mounted for reciprocation in said cylinder and along said tube, a by-pass between said inlet and the interior of said cylinder behind said piston providing a continuously open passage through which fluid can flow from said inlet into said cylinder at a relatively restricted controlled rate, a piston rod connected to said piston and movable therewith extending through the other end of said cylinder and having a tubular portion telescopically receiving said tube, a removable liner disposed in and reciprocable with the tubular portion of said piston rod and around said tube, and means holding said liner normally fixed in but removable from said rod, at least one portion of said liner snugly fitting the terminal portion of said tube to close said opening, and at least another portion of said rod being larger in diameter than said terminal portion and spaced therefrom to provide relatively unrestricted communication between said opening and said cylinder behind said piston.

6. A variable speed fluid motor comprising a cylinder having a fluid inlet at one end and a fluid outlet at the other end thereof, a tube extending from the inlet axially into said cylinder for conducting fluid from said inlet and having an enlarged terminal portion provided with a lateral discharge opening for said fluid, a piston mounted for reciprocation in said cylinder and along said tube, a by-pass between said inlet and the interior of said cylinder behind said piston providing a continuously open passage through which fluid can flow from said inlet into said cylinder at a relatively restricted controlled rate, a piston rod connected to said piston and movable therewith extending through the other end of said cylinder and having a tubular portion telescopically receiving said tube adapted to conduct fluid from said discharge opening into the cylinder behind said piston, and a removable liner in and movable with the tubular portion of said piston rod, said piston being removably connected to said rod and having a central opening through which said tube extends into the tubular portion of said rod and said liner and said piston overlapping said liner at said opening to hold the liner normally in said piston rod, a portion of said liner being of a diameter to snugly fit the terminal portion of said tube to close said opening and another portion of said liner being larger in diameter than said terminal portion so as to be spaced therefrom when in register with said opening whereby to provide relatively unrestricted communication between said opening and said cylinder behind said piston.

7. A variable speed fluid motor comprising a cylinder, a fitting removably mounted centrally in one end of said cylinder and detachably fastened thereto having an inlet through which fluid enters the cylinder, a tube carried by said fitting extending from the inlet into said cylinder for conducting fluid from said inlet and having an enlarged terminal portion provided with a lateral discharge opening for said fluid, a piston mounted for reciprocation in said cylinder and along said tube, a piston rod carried by and movable with said piston extending through the end of the cylinder remote from said fitting and having a tubular portion telescopically receiving said tube adapted to conduct fluid from said discharge opening into the cylinder behind said piston, a liner in and reciprocable with the tubular portion of said piston rod, means detachably holding said liner normally in said rod, a portion of said liner snugly fitting the terminal portion of said tube to close said opening and another portion of said liner being spaced from said terminal portion to provide relatively unrestricted communication between said opening and said cylinder behind said piston, said piston rod being disengageable from said piston

and removable from said cylinder to permit replacement of said liner, means providing a by-pass from said inlet to the cylinder behind said piston, means accessible from outside said fluid motor for controlling flow of fluid through said by-pass to restrict the rate at which fluid traversing said by-pass enters said cylinder, and means providing fluid outlets in the ends of the cylinder.

8. A variable speed fluid motor comprising a cylinder having inlet and outlet ports at opposite ends thereof, a longitudinal tube connected at one end to said cylinder extending axially therein and communicating at the connected end thereof with said inlet port so that fluid under pressure is admitted to said tube, a piston mounted for reciprocation in said cylinder and along said tube, a piston rod on and reciprocable with said piston having a tubular portion telescopically receiving said tube, said tube having a lateral orifice therein through which fluid passes from the tube into said rod and thence into said cylinder behind said piston, means carried by and movable with said piston rod slideable on said tube and cooperating with said orifice to open the same during selected portions of the piston travel and to close the same during other portions of piston travel, and a continuously open bypass affording a second means of communication and a controlled rate of fluid flow at all times between said tube and the portion of said cylinder behind said piston.

9. A variable speed fluid motor comprising a cylinder having inlet and outlet ports at opposite ends thereof, a longitudinal tube connected to said cylinder extending

5 axially therein and communicating with one of said ports, said tube having a lateral orifice therein through which fluid passes from the tube into said cylinder, a piston mounted for reciprocation in said cylinder and along said tube, a piston rod on and reciprocable with said piston having a tubular portion telescopically receiving said tube, said rod having portions of relatively small diameter and portions of relatively large diameter, the portions of relatively small diameter snugly fitting the tube and closing said orifice to close the same during the portions of piston travel when said relatively small diameter portions are in register with said orifice, the portions of relatively large diameter being spaced from said orifice to open the same during the portions of the piston travel when said large diameter portions are in register with said orifice, and a bypass between said tube and the portion of said cylinder behind said piston affording a restricted flow of fluid at all times between said tube and a portion of said cylinder behind said piston.
